(57) **CLAIM**

The ornamental design for a beverage machine, as shown and described.

DESCRIPTION

FIG. 1 is a top front perspective view of a beverage machine showing our new design;

FIG. 2 is a front elevation view of the beverage machine.

FIG. 3 is a rear elevation view of the beverage machine.

FIG. 4 is a top plan view of the beverage machine.

FIG. 5 is a bottom plan view of the beverage machine.

FIG. 6 is a left side elevation view of the beverage machine.

FIG. 7 is a right side elevation view of the beverage machine.

FIG. 8 is a bottom perspective view of the beverage machine.

FIG. 9 is a top perspective view of the beverage machine in an open position.

FIG. 10 is a front elevation view of the beverage machine in the open position.

FIG. 11 is a rear elevation view of the beverage machine in the open position.

FIG. 12 is a top plan view of the beverage machine in the open position.

FIG. 13 is a left side elevation view of the beverage machine in the open position.

(Continued)

FIG. 14 is a right side elevation view of the beverage machine in the open position; and,
 FIG. 15 is a bottom perspective view of the beverage machine in the open position.
 The broken lines in the drawing depict portions of the beverage machine that form no part of the claimed design.
